FORK OR SIMILAR ARTICLE OF FLATWARE

Stuart A. Young, South Meriden, Conn., assignor to The International Silver Company, Meriden, Conn., a corporation of Connecticut

Filed June 20, 1961, Ser. No. 65,652

Term of patent 14 years

(Cl. D54—12)

FIG. 1 is a front elevational view of a fork embodying the design;

FIG. 2 is a side elevational view;

FIG. 3 is an enlarged cross sectional view taken on line 3—3 of FIG. 1;

FIG. 4 is an enlarged cross sectional view taken on line 4—4 of FIG. 1;

FIG. 5 is an enlarged cross sectional view taken on line 5—5 of FIG. 1; and

FIG. 6 is an enlarged fragmentary view of a portion of the handle showing the detail of surface ornamentation.

The design is intended for use on sets comprising forks, spoons and knives and similar articles of flatware.

I claim:

The ornamental design for a fork or similar article of flatware, substantially as shown and described.
